(57) **CLAIM**

The ornamental design for a flow control assembly, as shown and described.

DESCRIPTION

FIG. 1 is a front perspective view of a flow control assembly illustrating our ornamental design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

Those portions of the Figures shown in broken lines and dashed lines are included for environmental purposes only and form no part of the claimed design.
